UNITED STATES PATENT OFFICE.

FRANKLIN A. ESPELAND, OF OAKES, NORTH DAKOTA.

SCRUBBING-MACHINE.

1,393,101.

Specification of Letters Patent. Patented Oct. 11, 1921.

Application filed October 29, 1920. Serial No. 420,345.

To all whom it may concern:

Be it known that I, FRANKLIN A. ESPELAND, a citizen of the United States of America, residing at Oakes, in the county of 5 Dickey and State of North Dakota, have invented certain new and useful Improvements in Scrubbing-Machines, of which the following is a specification.

My present invention relates to improvements in scrubbing machines designed especially for use in scrubbing floors, or other surfaces, and is of that type embodying a self contained reservoir or tank from which water is obtained and carried to the floor to 10 be scrubbed by successively dipping wipers, revolving with a rotor which latter is operated from traction wheels of the machine. The machine is hand operated in manner somewhat similar to carpet sweepers of this 15 type, but it will be understood that power devices may be applied to the machine as substitutes for the hand operating means.

The invention contemplates certain novel features of construction in this class of 20 scrubbing machines especially that of the reservoir which is made up of attached sections rendering facile access to the interior of the reservoir or casing in order that the rotor may be removed and replaced with convenience and despatch. The invention further consists in certain details of construction of the interior of the water tank or reservoir to insure proper wetting of the 25 wipers and assure the prevention of undue splashing and waste of water in connection with the wipers, and further meritorious features will be hereinafter pointed out and claimed in addition to those enumerated.

In the accompanying drawings I have 30 illustrated one complete example of the physical embodiment of my invention wherein the parts are combined and arranged according to the best mode I have thus far devised for the practical application of the 35 principles of my invention.

Figure 1 is a view in side elevation of a hand operated scrubbing machine involving my invention.

Fig. 2 is a longitudinal, vertical, sectional view through the reservoir and inclosed parts.

Fig. 3 is a detail perspective view of one of the buckets or receptacles, showing its attached wiper.

Fig. 4 is a detail plan view of the actuating mechanism and connections for the rotor.

Fig. 5 is a detail view partly in elevation showing the handle and frame construction, for adjustably supporting the actuating parts of the machine.

Fig. 6 is a plan view of the gage device for indicating the water level in the reservoir.

In the preferred form of the invention as shown in the drawings, the flat casing or reservoir is of size and shape to be readily 60 pushed across a floor, and under some pieces of furniture or household articles, the tank being made up of two sections 1 and 1^a and water tight to contain water that may be supplied through the top inlet 2. The respective sections 1 and 1^a are provided with side flanges 3 and 4, extending vertically at the outer sides thereof, and between the flanges a packing strip 5 may be interposed to make a water tight joint, and bolts 6 are 65 passed through the flanges to rigidly hold the two sections of the tank or casing together. The rear section is provided with a somewhat cylindrical formation or rounded end, while the rectangular reservoir or section 1 is provided with a transversely extending baffle plate 7 arranged at an incline and terminating near the top and bottom of the reservoir, to prevent or restrict the movement of the contained water, as a whole.

A second partition, as 8 extends transversely of the reservoir, terminating near the bottom of the reservoir. The end wall 9 of the reservoir, which separates the interior of the two sections terminates near the 70 top of the reservoir, in an inclined or obliquely arranged ledge 10, which projects into the section 1^a and provides a lip for an open throat portion 11 which affords communication between the two sections, at the top 75 of the reservoir.

At the rear of the machine, the rounded end of the section 1^a is provided with a rubbing device 12, preferably a piece of sheet rubber extending across the width of the machine at the rear of an opening 13 in the section 1^a, and a metallic spring clamping device 14 is utilized to secure this rubber strip to the section wall.

The whole machine is supported on the 105 pairs of wheels 15 and 16, the former at the front of the reservoir, and the latter at the rear of the machine and forming the traction or operating wheels for the actuating parts of the machine.

The traction wheels 16 are revoluble with their shaft 17, which is journaled in a U-

shape frame 18 that is pivoted on the operating shaft 19 of the machine, and the shaft 19 is journaled in the side walls of the casing section 1^a. The shaft 19 is located in the 5 axial center of the rounded section 1^a and extends transversely of the machine, projecting through the side walls thereof and having an additional support in the bracket 20 on the outside of the section 1^a as in Fig. 1.

10 The side arms of the frame 18 in which the shaft 17 is journaled are pivoted on the shaft 19. These pivoted arms are held or sustained in adjusted position with relation to the reservoir by means of a diagonal link 15 21 slotted at 22 to receive the bolt 23 at the upper end of a fixed bracket 24 attached to one side of the section 1^a. The lower end of this adjusting link is pivoted at 25 to the frame 18, and it will be apparent that 20 the slotted link may be moved through its slotted connection at 23 in order that the altitude of the rear end of the machine may be adjusted with relation to the floor or surface to be scrubbed.

25 Within the section 1^a and above the opening 13 therein is a rotor, including in its construction a pair of flat, end disks or heads 26 between which are supported a series of wipers 27, the heads being joined 30 by a central tubular hub 28 fixed to revolve with the shaft 19. The rotor is fashioned to form five buckets, each indicated as a whole by the numeral 28'. Each bucket or receptacle comprises a flat blade or plate 35 29 having a curved flange 30 extending the full length of the plate and attached to the hub 28. At its ends each plate has flanges 31 that are riveted or bolted to the respective heads 26 of the rotor, and each wiper 40 27 is attached to the inner side of its bucket by means of a wood cleat as 32. The rotor is thus equipped with five buckets or receptacles each of which is formed between the adjoining, tangentially arranged plates 29, 45 and each bucket opens in close proximity to the periphery of the rotor heads.

The wipers 27 are of suitable material, similar to that utilized for floor mopping or scrubbing, and the operation of the wipers 50 will be clear from a study of Fig. 2 wherein the rotor revolves in anti-clockwise direction, or to the left, and it will be seen that the wipers successively flop over into and through the throat 11 above the ledge 10, 55 overhanging the ledge into the space between the partition 8 and front wall 9 of

the tank. The movement of the machine, as it is manipulated by the operator, causes the water to splash about in the tank and within the space between the partition 8 60 and wall 9, thus insuring that the wiper as it flops over the ledge 10 will be supplied with water, and the bucket will also receive water splashed through the throat or opening 11. The wipers thus gather water for 65 wetting and washing the floors as the rotor revolves, and the rubber 12, which is in contact with the floor serves as a drying rubber.

70 The rotor is revolved from the shaft 17 through the train of gears 34, 35, 36, the former on shaft 17, the latter on shaft 19, and the intermediate wheel 35 being an idler between the driving and driven gears or pinions.

75 On the top of the tank a gage needle or indicator 37 is provided to show the quantity of water in the tank, the needle being revoluble with a worm screw 38 suitably supported and journaled within the tank 80 and actuated from a toothed quadrant 39, which is pivoted in the tank and has a buoyant float 40 suspended therefrom and supported upon the surface of the water in the reservoir. The outlet 41 at the side of 85 the tank or reservoir, is located near the bottom thereof and spring pressed to closed position. This outlet may be opened for emptying the contents of the tank by bearing upon the pivoted pedal 42 located at 90 the side of the tank in convenient position for depression by the foot of the operator, and connected as by a chain to the outlet 41.

95 Having thus fully described my invention, what I claim is—

The combination in a scrubbing machine of a casing having an open top end wall and a ledge thereon, a partition adjacent to said wall extending from the top of the casing and terminating near the bottom thereof, a section attached to said casing having an open bottom, a rotor journaled in said section forming a series of buckets, a wiper attached at the free edge of each bucket 100 adapted to flop over said ledge and pass through said open bottom, and means for 105 revolving the rotor.

In testimony whereof I affix my signature.

FRANKLIN A. ESPELAND.
